DESIGN FOR AN IDENTIFICATION PLATE FOR AN AUTOMOBILE OR SIMILAR AR- TICLE

Victor Salem, Kew Gardens, N. Y.

Application March 4, 1946, Serial No. 127,094

Term of patent 3½ years

(Cl. D14—6)

To all whom it may concern:

Be it known that I, Victor Salem, a citizen of the United States of America, residing at Kew Gardens, Long Island, county of Queens, and State of New York, have invented a new, original, and ornamental Design for an Identification Plate for an Automobile or Similar Article, of which the following is a specification, reference being had to the accompanying drawing, forming a part thereof.

Fig. 1 is a front elevational view of an identification plate for an automobile or similar article showing my new design, and

Fig. 2 is an edge view thereof.

The dominant features of my design are shown in full lines.

I claim:

The ornamental design for an identification

plate for an automobile or similar article, as shown and described.

VICTOR SALEM.
